UNITED STATES PATENT OFFICE.

ADOLPHUS BONZANO, OF PHILADELPHIA, PENNSYLVANIA.

STRUT-TIE FOR PREVENTING CREEPING OF RAILS.

SPECIFICATION forming part of Letters Patent No. 611,101, dated September 20, 1898.

Application filed May 10, 1898. Serial No. 680,309. (No model.)

To all whom it may concern:

Be it known that I, ADOLPHUS BONZANO, a citizen of the United States, residing in Philadelphia, Pennsylvania, have invented a certain Improved Strut-Tie for Preventing the Creeping of Rails, of which the following is a specification.

The object of my invention is to prevent the longitudinal creeping of railway-rails upon the ties caused by the passage of trains thereover. This object I attain by providing a device which is secured to the rails and to the ties in a manner fully described herein-after, reference being had to the accompanying drawings, in which—

Figure 1 is a perspective view of my improved device for preventing the creeping of rails upon the bed. Fig. 2 is a side view showing the device in position. Fig. 3 is a plan view with the rail in section. Fig. 4 is a view of a modification, and Fig. 5 is a view of a modified form of strut-tie.

Rails of railway-tracks are so laid that they are free to expand and contract, and consequently are also free to "creep," which is a longitudinal movement caused by the rolling-stock passing over them. While the rail must be free to expand and contract, the creeping must be checked. I accomplish this in the following manner:

A is the rail of a railway-track.

B are the ties, to which the rail A is secured by spikes b. I perforate the web a of the rail at or about the center of its length and secure thereto a strut-tie D, which is also secured to the ties.

The strut-tie is made, preferably, in the form shown in Fig. 1, having a flat central section d, adapted to rest against the web of the rail, and flat end sections d' d' at right angles thereto and adapted to rest on the ties and connected to the central section d by members d². The strut-tie is of such a length that the end sections will rest on two ties, as shown, with an intervening tie under the center where the strut-tie is secured to the rail.

The strut-tie D is secured to the rail by a bolt or rivet e and to the ties by spikes or screws f f.

I prefer to turn a lip d⁴ on each end of the strut-tie D, which enter the tie and thus take the strain off of the spikes f and give a wide

resisting-surface against longitudinal pressures.

I prefer to make the strut-tie by cutting a metal bar to the proper length and then bending it to shape, as shown in Fig. 1; but other methods of making the device may be employed without departing from my invention.

It will be noticed that when the strut-tie is in position if the rail has a tendency to move longitudinally in one direction one of the members d² will hold it under tension, while the other will hold it under compression. Thus the entire strut-tie is brought into action and there is no tendency to impart lateral motion to the rail, as one member d² counteracts the other member.

The strut-ties may be placed one on each side of the rail and bolted together and to the rail, or the strut-tie may be made in two parts, as shown in Fig. 4, one part D' on one side of the rail and the other part D² on the other side of the rail.

The strut-tie may be shortened to rest upon two adjoining ties; but I prefer to use the construction shown in Figs. 1, 2, and 3. The fastening of the strut-tie to the cross-tie B at the points shown does not interfere with the rail-spikes, and the ties will not tip under either torsional or compression strains.

In some instances the strut-tie may be made as shown in Fig. 5, having extended members d³, being of such a length as to rest each upon two ties, and I have shown in this figure the central portion having two holes for two securing-bolts. It will be understood that the strut-tie may have one or more bolt-holes and one or more holes for the spikes to secure it to the ties and that while I have shown the strut-tie made of a plain bar a flanged or other-shaped bar may be used without departing from my invention.

I claim as my invention—

1. As a new article of manufacture, a strut-tie made from a metal bar bent to form a central section and end sections connected to the central section by twisted members, substantially as described.

2. The combination of a rail, cross-ties on which it is mounted, a strut-tie having two members, said strut-tie being secured at or about the rail-center and the end of each

member secured to a cross-tie, so that each end of the rail is free to expand or contract, substantially as described.

3. The combination of a rail, cross-ties on which the rail is mounted, a strut-tie having a central section secured to the web of the rail, end sections secured to cross-ties and twisted members connecting the end sections to the central section, said strut-tie being of such a length as to extend from one tie to an-

other with a tie intervening, substantially as described.

In testimony whereof I have signed my name to this specification in the presence of two subscribing witnesses.

ADOLPHUS BONZANO.
